UNITED STATES PATENT OFFICE.

JOHN I. HAYNES, OF ST. LOUIS, MISSOURI.

CALCULATING-MACHINE.

1,112,612.

Specification of Letters Patent.

Patented Oct. 6, 1914.

Application filed July 14, 1911. Serial No. 638,533.

To all whom it may concern:

Be it known that I, JOHN I. HAYNES, a citizen of the United States, residing at St. Louis, Missouri, have invented a certain new and useful Improvement in Calculating-Machines, of which the following is a full, clear, and exact description, such as will enable others skilled in the art to which it appertains to make and use the same.

10 This invention relates to calculating machines, and particularly to that class of calculating machines in which the position of the type-bars is determined by means of stops or pins that are set up or moved into 15 operative position by the depression of the key levers of the machine.

One object of my invention is to provide a calculating machine of the type referred to that comprises fewer parts than the calculating machines which have heretofore been 20 in general use.

Another object is to provide a calculating machine in which the key levers have rigid arms that act directly upon the pins or stops 25 which limit the movement of the type-bars and thus determine the position of the type that are used to form the number or numbers which are to be printed.

Another object is to provide a calculating 30 machine which is so constructed that the operator can see what number has been set up in the machine prior to the printing operation, thereby enabling the operator to print the number if it is correct or restore the type-bars to normal position if the number 35 is incorrect.

Another object is to provide a calculating machine in which the printing of a number 40 of zeros is effected by merely depressing one of a group of keys and operating the handle of the machine, thereby overcoming the necessity of depressing one key a number of times whenever it is desired to print a number of zeros.

45 Another object is to provide a machine of the type referred to that comprises means of novel construction for preventing the operation of those type-bars which are not used during the printing of a number.

50 Another object is to provide a printing mechanism of novel construction that comprises only a few parts which can be manufactured and assembled cheaply. And still another object is to provide an accumulator 55 of novel construction that can be manufac-

tured at a low cost and which is so designed that it is not liable to get out of order easily.

Other objects and desirable features of my invention will be hereinafter pointed out.

Figure 1 of the drawings is a vertical sectional view of a calculating machine constructed in accordance with my invention; Fig. 2 is a top plan view, the casing of the machine being removed so as to more clearly illustrate the construction of the various elements of the machine; Fig. 3 is a rear elevational view; Fig. 4 is a vertical sectional view taken on approximately the line 4—4 of Fig. 3; Fig. 5 is a top plan view illustrating the construction and arrangement of the key levers; Fig. 6 is a front elevational view of the pin carriage; Fig. 7 is a detail horizontal sectional view taken on the line 7—7 of Fig. 6, looking in the direction indicated by the arrow; Fig. 8 is a vertical sectional view taken on the line 8—8 of Fig. 6; Fig. 9 is a side elevational view of one of the cams that forms part of the printing mechanism; Fig. 10 is an edge view of said cam; Fig. 11 is a side elevational view of one 80 of the adding wheels of the accumulator; Fig. 12 is an edge view of said wheel; Fig. 13 is an enlarged sectional view of the cam that shifts the accumulator frame and the mechanism that operates said cam; Figs. 14, 85 15 and 16 are sectional views taken on the lines 14—14, 15—15, and 16—16, respectively, of Fig. 13, looking in the direction indicated by the arrows; Fig. 17 is a rear elevational view of the parts shown in Fig. 90 13; Fig. 18 is a sectional view of the mechanism that restores the pin carriage to normal position; Figs. 19 and 20 are horizontal sectional views taken on the lines 19—19 and 20—20, respectively, of Fig. 18, looking 95 in the direction indicated by the arrows in Fig. 18; Fig. 21 is a side elevational view of part of the mechanism illustrated in Fig. 18; and Fig. 22 is a horizontal sectional view taken on the line 22—22 of Fig. 18, 100 looking in the direction indicated by the arrow.

Briefly described, my improved calculating machine consists of a plurality of type-bars preferably arranged in a vertical position and provided with plungers that carry type numerals. A set of digit keys are employed for setting up pins that coöperate with shoulders on the type-bars to limit the upward movement of said bars and thus

determine the position of the type thereon. Said pins are mounted in a transversely moving pin carriage, and a separate set of keys, which I will hereinafter refer 5 to as "zero keys," are employed for controlling the movement of the pin carriage transversely of the machine so as to permit said pin carriage to move different distances according to which zero key is depressed, 10 thereby permitting a plurality of zeros to be set up by the depression of a single key. A printing mechanism of novel construction co-operates with the plungers on the type-bars to force the type into engagement with the paper on the platen of the 15 machine, and the machine is also provided with an accumulator of novel construction for registering and adding the numbers that have been set up so as to permit a 20 total or sub-total to be printed. The transverse movement of the pin carriage in one direction is governed by an escapement mechanism controlled by the key levers of the machine, and the movement of said pin 25 carriage in the opposite direction is effected by means of a spring which is wound up or placed under tension during the forward stroke of the operating handle of the machine. A similar spring is used in the 30 accumulator for actuating a shaft provided with cams that co-operate with the pawls which feed the adding wheels of the accumulator forwardly, which spring is also wound up or placed under tension on the 35 forward stroke of the operating handle. The mechanisms which wind up these springs, and also the mechanism which imparts movement to the hammers of the printing mechanism are controlled and actuated by a reciprocating frame which I 40 will hereinafter refer to as a "rack frame," and which is operatively connected to the main operating shaft of the machine which carries the usual operating handle.

45 Referring to the drawings which illustrate the preferred form of my invention, 1 designates the base plate of the machine which is provided with brackets and standards for carrying the various elements of 50 the machine that are located inside of the casing. The paper on which the printing type operate is fed under a platen 3 arranged transversely across the top of the machine as shown in broken lines in Fig. 1, 55 the paper-feeding mechanism being omitted from the drawings as it forms no part of my present invention.

Type-bars.—A set of vertically disposed type-bars A, which are arranged in front 60 of the platen 3, are provided with movable type plungers that co-operate with a printing mechanism hereinafter described. Said type-bars are duplicates of one another, and each type-bar has ten spring-pressed type 65 plungers 4 which carry type that represent

the numerals 0, 1, 2, 3, 4, 5, 6, 7, 8 and 9, the "0" type being arranged at the upper ends of the type-bars, the numeral "1" type below the "0" type, the numeral "2" type below the "1" type, and so on, thus forming ten 70 horizontal rows of type, as shown in Fig. 3. Any suitable means may be employed for guiding the type-bars such, for example, as transversely arranged rods 5 that pass through vertically disposed slots 6 formed in 75 the type-bars, as shown in Fig. 4. The machine herein shown is provided with twelve type-bars but it is immaterial so far as my invention is concerned how many type-bars are used in the machine.

Controlling devices for type-bars.—Ten digit keys 7 which are arranged in two horizontal banks at the front of the machine are employed for operating pins or devices that limit the upward movement of the type-bars 80 A and thus determine the position of the type on said bars with relation to the platen 3 on which the type operate. The type-bar-controlling devices of the machine herein shown, consist of sets of pins 8 mounted 85 in a pin carriage B that moves transversely of the machine so as to bring the different rows of pins on said carriage into alinement with the type-bars. The pin carriage B is arranged at the rear of the type-bars, as 90 shown in Figs. 1 and 4, and it is preferably channel-shape in cross section and provided with top and bottom guides 9 that embrace a pair of horizontally arranged tracks 10 which extend transversely of the machine. 95 The pins 8 are arranged in vertical rows, each of which comprises eleven pins, and the number of vertical rows of pins on the carriage B corresponds to the number of type-bars so that in the construction herein shown the pin carriage is provided with twelve vertical rows of pins 8. Each digit key 7 is carried by a key lever 11 whose rear end is fulcrumed on a horizontally arranged shaft 12 that extends transversely 100 of the machine, and said key levers are provided at their rear ends with vertically disposed arms 13 that are arranged at the rear of the pin carriage, as shown in Figs. 1 and 3. The arm 13 on the lever which carries 110 the digit key "9" is provided at its upper end with a forwardly projecting extension 14 that is arranged in alinement with the top horizontal row of pins on the pin carriage; the arm 13 on the lever which carries 115 the digit key 8 being provided with an extension 14^a arranged in alinement with the second horizontal row of pins on the pin carriage, and the arms 13 on the levers which carry the digit keys 7, 6, 5, 4, 3, 2, 1 and 0, 120 being provided with extensions 14^b, 14^c, 14^d, 14^e, 14^f, 14^g, 14^h and 14ⁱ, respectively, that are arranged in horizontal alinement with the second, third, fourth, fifth, sixth, seventh, eighth and ninth horizontal rows 130

of pins on the pin carriage B, as shown clearly in Figs. 1 and 3. The space key 7^a is carried by a key lever 11 which is also provided at its rear end with an upwardly projecting arm 13 having an extension 14^a that is arranged in alinement with the bottom horizontal row of pins on the pin carriage. The arms 13 on said key levers are so shaped that all of the extensions previously described will be in vertical alinement with one another, as shown in Fig. 3, so that the first pin set up in the pin carriage will be in the first vertical row of pins, the second pin set up will be in the second vertical row of pins, and so on, as the pin carriage moves transversely to the left of the machine looking from the front of the machine. In the preferred form of my invention as herein shown, the arms 13 are rigidly connected to the key levers which carry same so that there will be no lost motion between the digit keys and the devices which move the pins on the pin carriage into operative position. Key levers 25 of the construction above described can be manufactured cheaply because they can be stamped out of sheets of metal, and as such a construction reduces the number of parts of the machine, the machine can be manufactured and assembled cheaply and is not as liable to get out of order as quickly as a structure in which a number of moving parts are employed for transmitting movement from the keys to the pins in the pin carriage. The digit keys are elevated or restored to normal position by means of coiled springs 15 connected to the arms 13 of the key levers and to a stationary bracket 16 on the frame of the machine, as shown in Fig. 1.

The pins 8 are preferably loosely mounted in a block or member on the pin carriage B so that when the extensions on the arms 13 of the key levers strike the rear ends of the pins the pins will be projected or moved forwardly beyond the front face of the pin carriage. The function of said pins, of course, is to limit the upward movement of the type-bars A and thus determine the position of the type on said bars with relation to the platen and the printing mechanism herein-after described that forces the type plungers 4 rearwardly or toward the platen. Each type-bar A is provided on its rear edge with a shoulder 17, shown in Figs. 4 and 8, that co-operates with the pins of the pin carriage so as to arrest the upward movement of the type-bars.

Type-bar actuating mechanism.—The means herein shown for raising and lowering the type-bars A consists of a plurality of type-bar-actuating members 18 oscillatingly mounted on a horizontal shaft 19 and provided at their rear ends with toothed segments 20 which co-operate with racks 21

formed on the front edges of the type-bars A adjacent the lower ends of said bars, as shown in Fig. 4, a member 18 being provided for each type-bar. I also prefer to provide the type-bar-actuating members 18 with segmental-shaped portions 22 that have numerals 23 on the front edges of same that correspond to the type numerals on the type-bars and which can be seen through a sight opening 24 in the casing of the machine at a certain period in the cycle of operations of the machine. The type-bar-actuating members 18 are so proportioned and arranged that the segmental-shaped portions 22 thereof which carry the numerals 23, will move relatively the same distance as the type-bars, thereby causing the numerals 23 on the members 18 which correspond to the numbers that have been set up in the machine, to be exposed to view through the sight opening 24 in the casing of the machine. The type-bar-actuating members 18 are rocked in a direction to impart upward movement to the type-bars by means of coiled springs 25 secured to said members 18 and to a stationary part 26 on the frame of the machine, as shown in Fig. 4, and said members are rocked in the opposite direction so as to lower the type-bars by means of a transversely arranged bar 27 arranged under the members 18 and carried by a pair of arms 28 loosely mounted on the main operating shaft C of the machine and provided at their lower ends with downwardly projecting extensions 29 to which coiled tension springs 30 are connected, as shown in Fig. 4, said springs tending to rock the arms 28 upwardly. The main operating shaft C is provided at one end with the usual operating handle C', and when said handle is pulled forwardly a pair of arms 31, which are rigidly secured to the main operating shaft C, engage lugs 28^a on the arms 28 and move said arms downwardly, thereby permitting the springs 25 to move the type-bar-actuating members 18 in the direction that causes the type-bars to move upwardly. When the operating handle C' is released, a coiled spring 32, which is connected at one end to an arm 33 on the main operating shaft C and at its opposite end to a stationary bracket 34, as shown in Fig. 1, causes the operating handle and shaft C to move in the reverse direction back to normal position and thus permits the spring 30 shown in Fig. 4, to restore the arms 28 which carry the rod 27 that bears against the under sides of the type-bar-actuating members 18, the springs 30 being enough stronger than the springs 25 to overcome the force of the springs 25 and to cause the members 18 to move the type-bars A downwardly before the operating handle of the machine is completely restored to normal position. By providing a separate spring-actuated member 18

for each type-bar, each type-bar can be arrested at any point in its upward movement without affecting the other type-bars, and by providing a means separate and distinct from the main operating shaft of the machine for actuating the type-bar-operating members 18 I am able to use the latter portion of the return stroke of the operating handle for setting in operation certain mechanism that does not operate until after the type-bars have been lowered or restored to normal position.

Escapement mechanism for pin carriage.—The means herein shown for moving the pin carriage B to the left, as viewed from the front of the machine, consists of a coiled spring 35 connected to said carriage and to a stationary bracket on the frame of the machine, as shown in Fig. 3, and an escapement mechanism is provided for permitting the carriage to move in this direction step-by-step so as to successively bring the vertical rows of pins on the pin carriage into alignment with the type-bars. The escapement mechanism is controlled by the key levers of the machine, and it consists of an escapement shaft 36, a pinion 37 on said shaft that meshes with a rack 38 on the lower edge of the pin carriage B, as shown in Fig. 4, an escapement wheel 39 on the escapement shaft, and a rock arm 40 provided with a rigid tooth 40^a and a spring tooth 40^b that coöperate with the escapement wheel 39. The arm 40 is secured to a rock shaft 41 provided with a downwardly projecting pair of arms 42 that carry a rod 43 which extends transversely of the machine under the digit key and space key levers 11. When the space key or either of the digit keys is depressed the arm 40 will move downwardly and thus bring the rigid tooth 40^a thereon into engagement with the escapement wheel 39 and simultaneously carry the spring tooth 40^b out of engagement with said escapement wheel, said spring tooth springing laterally as soon as it is released so that it can engage another tooth of the escapement wheel when the arm 40 moves upwardly. On releasing the key that has been depressed the arm 40 moves upwardly, thereby carrying the rigid tooth thereon out of engagement with the escapement wheel and thus temporarily releasing the escapement shaft so that the spring 35 can move the pin carriage B one step to the left, the movement of the escapement shaft and pin carriage being arrested as soon as the spring tooth 40^b on the arm 40 has been compressed or moved into engagement with the rigid tooth 40^a on said arm. The pin carriage is moved to the right or restored to normal position by mechanism which will be hereinafter described.

Stop-plate for idle type-bars.—In view of the fact that the type-bars mesh

at all times with the toothed segments 20 on the type-bar-operating members 18 which are free to oscillate whenever the operating handle of the machine is pulled forwardly, some means must be provided for preventing upward movement of those type-bars which are not used during the printing of a number. For example, if the number to be printed is 972, only the three right-hand type-bars, viewed from the front of the machine, will be used, and the other nine type-bars will perform no function during this operation. The means herein shown for preventing upward movement of the idle type-bars, or those that are not used during the printing of a number, is of novel construction and consists of a stop plate 44 on the pin carriage B that moves forwardly automatically when the pin carriage reaches a certain position in its travel to the left and thus acts as a stop which limits the upward movement of all of the type-bars to the left of the type-bars that are being used to print the number. Said stop plate 44 is slidably mounted on the lower flange of the pin carriage, as shown in Figs. 6 and 7, and it is provided with inclined slots 45 through which studs 46 on said lower flange project. A coiled contractile spring 47 which is connected to the stop plate 44 and to the pin carriage in the manner shown in Fig. 7, tends to move said stop plate to the right so as to hold said plate in operative position or cause it to project forwardly beyond the front of the pin carriage. The means which retracts the stop plate 44 or moves it rearwardly so that it does not project beyond the front of the carriage, consists of a lug 48 on the stop plate that engages the stationary lug 49 on the lower track 10 on which the carriage slides just before the carriage reaches the end of its movement to the right or back to normal position. When the pin carriage is in normal position, or at the end of its stroke to the right, the stop plate 44 will occupy the position shown in Figs. 6 and 7, the spring 47 being under tension at this time. When said pin carriage starts to move to the left during the operation of setting up the type that form the number to be printed, the stop plate 44 starts to move forwardly or to project beyond the front face of the pin carriage on account of the fact that the spring 47 tends to hold the lug 48 on the stop plate in engagement with the stationary lug 49 on the carriage track, and the studs 46 on the carriage which are moving with the carriage, exert sufficient pressure on the edges of the inclined slots 45 in the stop plate to move the stop plate forwardly or beyond the front face of the carriage. After the pin carriage has moved a certain distance to the left, say, for example, two spaces, a shoulder 50 on the carriage engages the stop

plate and thus causes the stop plate to move bodily with the carriage, the stop plate remaining in its forward position during the rest of the stroke of the pin carriage to the left. When the pin carriage is returned to normal position, or moved to the right, the lug 48 on the stop plate strikes the rigid lug 49 before the carriage reaches its limit of movement to the right and thus causes the stop plate to be moved rearwardly or into an inoperative position so as not to interfere with the operation of taking a total or a sub-total.

Printing mechanism.—The printing mechanism preferably consists of a plurality of pivotally mounted hammers 51 arranged in front of the type-bars, as shown in Fig. 4, and loosely mounted on a transversely extending shaft 52, said hammers being guided by a comb plate 53 and one hammer being provided for each type-bar. A plurality of bell crank levers 54 are connected by means of links 55 to the lower ends of the hammers 51, as shown in Fig. 4, and a cam shaft 56 that is provided with a plurality of cams 57 is employed for rocking the bell crank levers 54 so as to force the hammers 51 into engagement with the type plungers 4 of the type-bars, said bell crank levers being moved in the reverse direction by means of leaf springs 58, it being, of course, understood that a bell-crank lever is provided for each hammer. If desired, the cam shaft 56 of the printing mechanism can be provided with a single cam which operates all of the bell crank levers 54 simultaneously, but I prefer to provide the shaft 56 with a plurality of separate and distinct cams, one for each bell crank lever 54, which cams are so arranged that the hammers 51 will be operated progressively, thereby requiring less power to operate the cam shaft 56 than if said shaft were provided with a single cam that operated all of the bell crank levers 54 simultaneously.

Each of the cams 57 occupies a different position on the cam shaft 56, each cam being arranged a slight distance in advance of the one at the left of same. The particular construction of these cams and the way in which they are mounted on the shaft 56 is novel, and is one of the important features of my machine as it reduces the cost of manufacture and overcomes the necessity of providing a cam of special design for each bell crank lever 54. By referring to Fig. 4 it will be seen that the cam shaft 56 has a sleeve 59 rigidly secured thereto which is provided with twelve teeth. Each of the cams 57 is connected to a disk 57^a provided at its center with an opening that corresponds to the shape of the sleeve 59, thereby enabling the disk to be arranged in any desired position on the sleeve 59 so as to locate the cam 57 on the

disk in proper position. Of course, if the machine were provided with fourteen hammers, fourteen cams would be used and the sleeve 59 would be provided with fourteen teeth. The cam shaft 56 is rotated in the direction indicated by the arrow in Fig. 4 by means of mechanism that cooperates with a reciprocating rack frame F which will be hereinafter described, said mechanism consisting of an oscillating member 60, shown in Fig. 1, which is provided with a toothed segment 61 that meshes with a pinion 62 loosely mounted on the cam shaft 56 and provided with a pawl 63 that is adapted to engage a ratchet wheel 64 on the cam shaft and impart rotary movement to said shaft when the oscillating member 60 is moved in one direction. On the reverse stroke of the oscillating member 60 the pawl 63 will travel idly over the ratchet wheel 64 and thus permit the cam shaft to remain at rest.

Mechanism for restoring pins on pin carriage.—The means for restoring the pins 8 on the pin carriage B, or moving said pins into an inoperative position, consists of a comb plate 65 arranged on the rear side of the pin carriage and provided with slots through which the pins project, as shown in Fig. 3, each of the pins 8 being provided with a head 8^a that the comb plate engages when said plate is moved rearwardly away from the carriage. The comb plate 65 is carried by pairs of links 66 that are connected to the top and bottom flanges of the pin carriage, as shown in Figs. 2 and 3, and coiled springs 67 are connected to the comb plate and to the pin carriage, as shown in Fig. 2, so as to normally hold said comb plate in inoperative position against the rear side of the carriage. At a certain period in the cycle of operations of the machine the comb plate 65 is moved rearwardly away from the pin carriage by means of a lever 68 that is actuated by a cam 69 on a vertically disposed spring-operated shaft 70 that forms part of the carriage-restoring mechanism and which will be hereinafter described, the cam 69 rotating in the direction indicated by the arrow in Fig. 2 so that when it strikes the front end of the lever 68 the rear end of said lever will move to the left and thus force the comb plate to the left and also rearwardly, said plate striking against the heads 8^a on the pins and thus withdrawing them from operative position.

Zero keys.—In order that the operator will not have to press one key a number of times whenever it is desired to print a number of zeros, means is provided for permitting the pin carriage to move a number of spaces to the left whenever one of a certain group of keys is depressed. Said means is controlled by two banks of keys 71 which

6

I will hereinafter refer to as "zero" keys, the machine herein shown having eight zero keys which are numbered 2 to 9, inclusive, as shown in Fig. 5. The zero keys 71 are carried by key levers 72 which are pivotally mounted intermediate their ends on a horizontal shaft 73, as shown in Figs. 1 and 4, and each of said key levers is provided adjacent its rear end with an upwardly projecting lug 74 which passes through a slotted guide plate or comb plate 75 secured to a stationary part of the frame of the machine. The rear ends of all of the zero key levers pass under a bail 76 secured to a pair of bell crank-shaped arms 77 mounted on a horizontal shaft 78. A horizontally disposed rack bar 79 which is reciprocatingly mounted in the arms 77, is adapted to engage a pinion 80 on the escapement shaft 36 whenever any of the zero keys are depressed. Said rack bar 79 is provided on its under side with a stop 81 that co-operates with the lugs 74 on the zero key levers, and a coiled expansion spring 82 is mounted on a reduced portion of the rack bar 79 for returning said rack bar to normal position, as hereinafter described.

The shaft 41 to which the arm 40 of the escapement mechanism is connected, is provided with a pair of arms 83 which carry a rod 84 that extends transversely under the zero key levers, as shown in Fig. 4, so that when any of the zero key levers is depressed the arm 40 of the escapement mechanism will be moved downwardly far enough to carry both the rigid tooth and the yielding tooth on said arm completely out of engagement with the escapement wheel 39 and thus release the escapement shaft which is then free to rotate under the influence of the spring 35 which is connected to the pin carriage. Consequently, whenever one of the zero key levers is depressed the pin carriage will jump quickly to the left until it is arrested by the engagement of the stop 81 on the rack bar 79 with the lug 74 on the depressed zero key lever, it being, of course, understood that the rack bar 79 moved into engagement with the pinion 80 on the escapement shaft when the zero key lever was depressed. In view of the fact that the lugs 74 on the zero key levers are arranged at different distances from the righthand side of the machine, the pin carriage will move to the left different distances according to which zero key is depressed. If the number being printed contains three zeros the operator depresses the zero key marked "3," therefore causing the escapement mechanism to be thrown out of operation and the rack bar 79 to be thrown into mesh with the pinion 80 which moves said rack bar to the left until the stop 81 thereon engages the lug 74 on the lever 72 of the zero key 3. If the number to be printed has four zeros the zero key marked "4" is depressed, the key lever which carries the zero key 4 being so arranged with relation to the lever that carries the zero key 3 that the pin carriage will move one space farther to the left before it is arrested by the engagement of the lug 74 on the key lever and the stop on the rack bar 79 than when the zero key 3 is depressed. When the zero key is released the escapement mechanism will be again thrown into operation so as to lock the pin carriage in the position to which it has been moved, the bell-crank-shaped arms which carry the rack bar 79 being rocked downwardly by means of springs 85 so as to disengage the rack 79 from the pinion 80 and thus permit said rack to be restored to normal position by means of the coiled spring 82 which was compressed when said rack moved to the left with the pin carriage. The pins in the pin carriage B are not used during the printing of a number that contains a plurality of zeros; or, in other words, the depression of any of the zero keys 71 has no effect on the pins in the pin carriage.

The means which controls the position of the type-bars when a plurality of zeros are to be printed side by side, consists of a plate 86 mounted on the front face of the pin carriage B which I will hereinafter refer to as a "zero stop plate." Said zero stop plate is provided on its rear side with horizontally disposed ribs 87 that fit in guides or grooves 88 formed in the pin carriage B, as shown in Figs. 1 and 6, and on the lower edge of said zero stop plate is a shoulder 89 which co-operates with a locking plunger 90 that normally prevents the zero stop plate from moving transversely with the pin carriage, the machine being so designed that the pin carriage can move its full stroke to the left while the zero stop plate 86 remains at rest. When the locking plunger 90 is depressed, however, or withdrawn from engagement with the shoulder 89 on the zero stop plate, said plate will start to move with the pin carriage, and as it projects a slight distance beyond the front face of the pin carriage, as shown more clearly in Fig. 1, the lower edge 91 of same will form a stop that co-operates with the type-bars which align with the lower edge 91 of the zero stop plate so as to limit the upward movement of said type bars. For example, if the number being printed is 972,000, the zero stop plate will remain at rest during the first three steps of the pin carriage to the left or when the numbers 972 are being set up, but when the zero key 3 is depressed the locking plunger 90 will be withdrawn from engagement with the shoulder 89 on the zero stop plate and thus permit said plate to move with the pin carriage during the last portion of the stroke of the pin carriage, thereby causing said plate to

be arranged in alignment with the three right-hand type-bars and thus permitting said type-bars to move upwardly one space so as to bring the zero type thereon into a horizontal alignment with the type 9, 7 and 2 on the three type-bars to the left which have been set up by the depression of the digit keys 9, 7 and 2. The locking plunger 90 has its lower end pivotally connected to an arm 92 on a rock shaft 93 that is provided with a bail 94 which extends over the tail-ends of the zero key lever 72, as shown in Figs. 1, 4 and 5, so that when any of the zero key levers are depressed the plunger 90 will 10 be withdrawn from engagement with the zero stop plate 86 which is then free to move with the pin carriage B. When the pin carriage is moved to the right, back to normal position, the zero stop plate will move with 15 it until said plate strikes the stop 95 on the upper track 10 on which the pin carriage travels and the locking plunger 90 will be moved upwardly into engagement with the zero stop plate by means of a spring 96 connected to the bail of the rock shaft 93, as 20 shown in Fig. 1.

Accumulator.—The accumulator consists of a set of adding wheels 97 loosely mounted on a transversely arranged shaft 98 journaled in a frame 99 which is secured to a horizontal rock shaft 100 that is arranged at the rear of the type-bars, as shown in Fig. 4, each of said adding wheels coöperating with one of the type-bars and being 30 provided with ten teeth that mesh with a rack 101 on its coöperating type-bar when the accumulator frame 99 occupies a certain position. Each adding wheel is provided on one side with a lug 102 that 35 coöperates with a shoulder 103 on a stop pawl 104 which is pivotally mounted on the accumulator frame 99, as shown in Fig. 4. A stop pawl 104 is provided for each adding wheel of the accumulator except the wheel 40 of highest order, and said adding wheels and stop pawls are so arranged that the upper end of each stop pawl will be moved rearwardly once during each complete rotation of the adding wheel with which it 45 coöperates, the stop pawls being provided with cam projections 105 which the lugs 102 on the adding wheels engage during the last step or movement of the adding wheel, or after said adding wheel has traveled nine 50 spaces in anti-clockwise direction. Pawls or dogs 106 which are pivotally connected to the upper ends of the stop pawls 104 coöperate with the adding wheels to move them forwardly, said dogs being so arranged 55 that each dog coöperates with the adding wheel to the left of the one that coöperates with the stop pawl on which the dog is pivotally mounted. That is to say, the stop pawl which coöperates with 60 the units-wheel of the accumulator is pro-

vided with a dog or pawl 106 which coöperates with the tens-wheel of the accumulator so that the tens-wheel will be moved one step forwardly every time the units-wheel makes one complete revolution. The 70 dogs 106 are held in engagement with their respective adding wheels by means of flat leaf springs 107, and each stop pawl is provided at its lower end with an arm or extension 108 which coöperates with a spring 75 detent 109 on the accumulator frame, as shown in Fig. 4, that holds the stop pawl in a certain position after it has been operated by the adding wheel which coöperates with same. When the type-bars move upwardly 80 the accumulator frame which carries the adding wheels, is swung rearwardly so that the racks 101 on the type-bars will not engage said adding wheels on the upward stroke of the type-bars. On the downward stroke of the type-bars, however, the accumulator frame swings forwardly back to normal position so that the racks 101 on the type-bar will engage the adding wheels and thus cause the numbers that have been set 85 up in the machine to be registered in the accumulator. The stop pawls are moved forwardly so as to cause the dogs 106 thereon to impart forward strokes to the adding wheels by means of cams 110 on a cam shaft 95 111 that rotates in the direction indicated by the arrow in Fig. 4, one cam being provided for each stop pawl 104, and each of said stop pawls being provided on its rear edge with a lug 112 that is adapted to be engaged 100 by said cam. The cams 110 are preferably of the same construction as the cams that are mounted on the shaft 56 of the printing mechanism previously described, and they are so arranged on the cam shaft 111 that the 105 stop pawls will be operated progressively from the lowest to the highest order; or, in other words, the stop pawl that coöperates with the units-wheel is operated first, the one which coöperates with the tens-wheel next, 110 and so on. The accumulator comprises the usual units-wheel, tens-wheel, hundreds-wheel, etc., and said wheels are so arranged that they will coöperate with the type-bars which carry the type that forms the units, 115 tens and hundreds, etc. of the number being printed, the units-wheel coöperating with the type-bar at the righthand side of the machine, the tens-wheel coöperating with the second type-bar from the righthand side 120 of the machine, etc., across the machine. Normally, the lugs 102 on the adding wheels of the accumulator rest upon shoulders 103 of the stop pawls, and when a number has been set up in the machine the adding wheels which coöperate with the type-bars that have been used for this operation, will be moved forwardly in anti-clockwise direction so as to move the lugs 102 away from their coöperating shoulders 103. If the first 125

number that is printed is 972 the hundreds adding wheel of the accumulator, which coöperates with the third type-bar from the righthand side of the machine, will be moved forwardly nine spaces; the tens-wheel, which coöperates with the second type-bar, will be moved forwardly seven spaces, and the units-wheel, which coöperates with the first type-bar will be moved forwardly two spaces. If the next number that is printed is 18 the tens-wheel will be moved forwardly one space and the units-wheel will be moved forwardly eight spaces. On the last step of the units-wheel 15 the lug 102 thereon engages the projection 105 on the stop pawl that coöperates with said units-wheel and will thus move said stop pawl rearwardly, thereby causing the dog 106 thereon to move rearwardly one tooth over the tens-wheel with which said dog coöperates, the stop pawl being retained in the position to which it has been moved by means of the spring detent 109 on the accumulator frame. Thereafter, this stop 20 pawl is moved forwardly by means of the cam 110 which coöperates with same and this forward movement of the stop pawl causes the dog 106 thereon to move the tens-wheel one step forwardly so as to register the total 25 990 in the accumulator. If it is desired to print this total, the operator depresses a total key hereinafter described.

The means which swings the accumulator frame 99 rearwardly consists of a cam 113, 30 shown in Figs. 13, 16 and 17, that coöperates with an arm 114 secured to the shaft 100 which carries the accumulator frame. This cam 113 is connected to a long sleeve 115 that is loosely mounted on a horizontal shaft 116 which extends transversely of the machine, and said sleeve is provided with a pinion 117 that normally meshes with a rack 118 on the rack frame F previously described said rack frame being reciprocatingly mounted on horizontally arranged tracks or guides 119 located adjacent the righthand side of the machine and extending from the front to the rear of the machine at approximately right angles to the horizontal shaft 116 which supports the sleeve of the cam 113.

Primary actuating mechanism.—As the rack frame F is the means which imparts movement to the mechanism that operates the cam shaft 56 of the printing mechanism and also to the mechanisms which operate the cam shaft 111 of the accumulator mechanism, and the shaft 70 which forms part of the pin carriage restoring mechanism, I will 55 refer to said rack frame F as the "primary actuator" of the machine. Said rack frame F is moved forwardly and backwardly by means of a pair of pinions 120 that mesh with rack teeth 118 and 118^a on the rack frame, said pinions 120 being secured to a

horizontal shaft 121 provided with a pinion 122 of smaller diameter that is arranged between the pinions 120, as shown in Figs. 1 and 2. This intermediate pinion 122 meshes with a toothed sector 123 that is rigidly connected to the main operating shaft C of the machine, as shown in Fig. 1. When the operating handle C' is pulled forwardly the toothed sector 123, which meshes with the pinion 122, will cause the pinions 120 to rotate rearwardly and thus impart a forward stroke to the rack frame F. This movement of the rack frame causes the cam 113 to rotate in the direction indicated by the arrow in Fig. 16 because the pinion 117, carried by the sleeve 115, is in mesh with the rack 118 on the rack frame. This movement of the cam 113 causes the arm 114 to swing downwardly and thus rock the accumulator frame rearwardly so that the adding wheels thereon will not engage the type-bars when said type-bars move upwardly. The accumulator frame is held rearwardly, or in an inoperative position, until the forward stroke of the operating handle C' is completed, the cam 113 being so designed that it makes one complete revolution during the forward stroke of the operating handle so that the arm 114 will move back to its original position on the low part of the cam before the operating handle starts to move rearwardly. On the return stroke of the operating handle, the rack frame F moves rearwardly but the sleeve 115, to which the cam 113 is connected, remains at rest so as to permit the 100 accumulator frame to remain in its operative position and thus cause the adding wheels thereon to be engaged by the racks 101 on the type-bars when said type-bars move downwardly. The means by which I accomplish this, namely, cause the cam 113 to rotate on the forward stroke of the operating handle and to remain at rest on the return stroke of the operating handle, consists of a pawl and ratchet connection between the 105 pinion 117 and the sleeve 115 which carries the cam 113, said pinion being provided with a pivotally mounted pawl 124 that engages a one-tooth ratchet wheel 125 rigidly secured to the sleeve 115 when the rack frame moves 110 forwardly, and which slides freely in the reverse direction over said ratchet wheel when the rack frame moves rearwardly, it being, of course, understood that the pinion 117 is 115 loosely mounted on the sleeve 115.

The means which transfers movement from the rack frame F to the oscillating member 60 of the printing mechanism consists of a short rack bar 126 slidingly mounted in a guideway, as shown in Figs. 1 and 2, 120 and provided with a laterally projecting lug 127 that is adapted to be engaged by a laterally projecting lug 127^a on the rack frame F when said rack frame moves forwardly, the teeth of the rack bar 126 meshing with a 130

toothed segment on the lower end of the oscillating member 60 of the printing mechanism. The lug 127^a on the rack frame does not engage the lug on the rack bar 126 until just the last part of the forward stroke of the operating handle of the machine so that the printing mechanism does not operate until after the type-bars have been positioned. On the return stroke of the rack frame F the oscillating member 60 and the rack bar 126 are restored to normal position by means of a coiled spring 128, shown in Fig. 1, that is connected at one end of the oscillating member 60 and at its opposite end to a stationary part of the frame of the machine.

The vertically disposed shaft 70 which forms part of the mechanism for restoring the pin carriage to normal position, and also for withdrawing the pins or moving them rearwardly into an inoperative position, is actuated by means of a clock-spring 129 secured at one end to said shaft and at its opposite end to a stationary part of the frame of the machine, said shaft being rotated in the opposite direction so as to wind up the spring 129 by means of mechanism that cooperates with the rack frame F. In Figs. 18 to 22, inclusive, I have illustrated the shaft 70 and the mechanism that is employed for winding up the spring 129 which actuates said shaft. By referring to said figures it will be seen that the rack frame F is provided on one side with a rack bar 130 that meshes with a pinion 131 which is loosely mounted on the shaft 70. Said pinion is provided on its upper side with a lug 132 that cooperates with a lug 133 on the under side of a disk 134 which is pinned to the shaft 70. A disk 135 which is loosely mounted on the shaft 70 and arranged above the disk 134, is provided on its under side with a cam track 136 which receives a spring-actuated locking dog 137 that is mounted on the disk 134, and said disk 135 is also provided on its upper side with a toothed segment 138 that meshes with rack teeth 139 on the front face of the pin carriage B, said rack teeth 139 being located adjacent the lower righthand edge of the pin carriage, as shown in Figs. 1, 2 and 6. A bell-crank-shaped locking dog 140, which is pivotally mounted on a stationary part of the frame of the machine, cooperates with a notch 141 on the periphery of the disk 134 to lock said disk, and a cam 142, which is arranged on one side of the rack frame F, as shown in Figs. 20 and 21, engages said locking dog on the return stroke of the rack frame and trips it or moves it into an inoperative position against the force of the spring 143 so as to release the disk 134, said cam 142 also cooperating with the spring-actuated locking dog 137 in certain positions of the rack frame F. The pinion 131 on the shaft 70 is normally held

in engagement with a stationary collar 145 on said shaft by means of a coiled expansion spring 146 that exerts downward pressure on said pinion and thus holds it in mesh with the rack 130 on the rack frame.

Prior to the setting up of a number and the printing of same, the parts just described occupy the positions shown in Figs. 18 to 21, inclusive. When the digit key levers are depressed so as to cause the pin carriage B to move transversely to the left of the machine, the disk 135 which carries the cam track 136 will rotate in anti-clockwise direction, looking at Fig. 20, because the toothed segment 138 on said disk meshes with the rack 139 on the pin carriage, said disk coming to rest as soon as the pin carriage stops. If the pin carriage moved three spaces to the left the disk 135 will move relatively the same distance and thus cause the shoulder 136^a of the cam track on the under side of said disk to occupy approximately the position indicated by broken lines in Fig. 20. The shaft 70 remains at rest during this operation but when the operating handle C' of the machine is pulled forwardly the rack frame F moves forwardly and the rack 130 on said frame rotates the pinion 131 in anti-clockwise direction, thereby causing the lug 132 on said pinion to engage the lug 133 on the under side of the disk 134 and rotate said disk and the shaft 70 to which it is connected, the machine being so designed that the disk 134 will make one complete revolution on the forward stroke of the rack frame F. The forward movement of the rack frame carries the cam 142 thereon out of engagement with the bell-crank-shaped locking dog 140 and thus permits said dog to move into engagement with the periphery of the disk 134 so that it will spring into the notch 141 in said disk and thus lock same when the movement of the disk is completed. When the rack frame F moves rearwardly the cam 142 thereon trips the dog 140 just before the return stroke of said frame is completed, thereby releasing the disk 134 and thus permitting the spring 129 to rotate the shaft 70. During this movement of the shaft 70 the spring-actuated locking dog 137 on the disk 134 engages the shoulder 136^a of the cam track on the under side of the disk 135 and thus moves said disk back to normal position, which operation also restores the pin carriage to normal position on account of the fact that the toothed segment 138 on the disk 135 meshes with the rack 139 on the pin carriage B. The cam 142 on the side of the rack frame F is so arranged that it engages the dog 137 on the disk 134 and moves it out of engagement with the shoulder 136^a of the cam track just before the rack frame completes its rearward stroke so that the disk 135 and the toothed segment 138

138 thereon are free to rotate when the pin carriage B again starts to move to the left.

The cam 69 on the upper end of the shaft 70 which actuates the comb plate 65 that withdraws the pins on the pin carriage from operative position, is provided on its under side with a spring-actuated pawl 69^a that coöperates with a one-toothed ratchet 69^b on the shaft 70, as shown in Fig. 19, so that the cam 69 will remain at rest when the spring 129 is being wound up and will rotate with the shaft 70 when said shaft is released from the influence of the locking dog 140, as previously described.

The cam shaft 111 that actuates the stop pawls 104 of the accumulator is operated in a similar manner to the shaft 70 just described by means of a spring 147 which is connected at one end to said shaft and at its other end to a stationary part of the frame of the machine. The rack frame F is provided on its under side with a rack bar 148 which meshes with a pinion 149, as shown in Fig. 1, said pinion being connected to a disk 149^a loosely mounted on the cam shaft 111 and provided with a lug 150 that coöperates with a lug 151 on a disk 152 which is pinned to the cam shaft 111. A spring-actuated locking dog 153, which is pivotally mounted on a stationary part of the frame of the machine, coöperates with a notch 154 in the periphery of the disk 152 to lock said disk, and a cam 155, which is arranged on the rack frame F, operates to trip said dog 153 so as to release the disk 152 and the cam shaft 111. When the rack frame F moves forwardly the pinion 149 will rotate and thus cause the lug 150 to engage the lug 151 and impart rotary movement to the disk 152 and the cam shaft 111 to which said disk is connected, the machine being so designed that said disk and shaft make one complete revolution upon the forward stroke of the rack frame F. At the end of this complete revolution the cam shaft 111 is locked by means of the locking pawl 153 which moved into engagement with the periphery of the disk 152 when the rack frame F moved forwardly. The spring 147 which is connected to the cam shaft 111 of the accumulator is now wound up, and when the rack frame F moves rearwardly and trips the locking pawl 153 said spring will unwind and thus rotate the cam shaft 111 in the direction indicated by the arrow in Fig. 4, the cams 110 on said shaft engaging the stop pawls of the accumulator which have been moved into operative position by the adding wheels of the accumulator, as previously described. At the time the cam shaft 111 of the accumulator is being rotated backwardly to wind up the spring 147, the frame of the accumulator is in its rearward or inoperative position so that the stop pawls of the accumulator lie out of the path of movement of the cams on

the cam shaft 111 and thus cannot prevent said cam shaft from rotating backwardly in the manner just described.

Total key.—In order that a total may be taken of the numbers that have been set up in the machine, the machine is provided with a total key 156 mounted on a key lever that has a cam 157 secured thereto, as shown in Fig. 1. Said cam coöperates with a disk 158 on the sleeve 115 that carries the cam 113 which causes the accumulator frame to swing rearwardly, and when said total key 156 is depressed the cam 157 engages the disk 158 and moves the sleeve 115 laterally in the direction indicated by the arrow in Fig. 13, the sleeve 115 being held in normal position by means of a coiled expansion spring 159 which is also shown in Fig. 13. The cam 157 is so designed that the lateral movement imparted to the sleeve 115 carries the pinion 117 on said sleeve out of engagement with the rack 118 of the rack frame F, as shown in Fig. 17. Consequently, if the operating handle of the machine is pulled forwardly when the total key 156 is depressed, the cam 113, which controls the movement of the accumulator frame, will remain at rest on the forward stroke of the rack frame and thus cause the accumulator frame to remain in its normal position so that the racks 101 on the type-bars that have been used in setting up the numbers which are to be totaled, will engage the adding wheels of the accumulator when said type-bars move upwardly and will thus move said adding wheels backwardly until the lugs 102 thereon engage the shoulders 103 on the stop pawls of the accumulator.

If the numbers which have been set up in the machine are 972 and 18, the hundreds-wheel of the accumulator will rotate rearwardly nine steps before it is arrested by the stop pawl and thus permit the third type-bar from the righthand side of the machine to move upwardly nine spaces, the tens-wheel will also rotate rearwardly nine steps before it is arrested by the stop pawl and thus permit the second type-bar from the righthand side of the machine to move upwardly nine spaces, and the units-wheel will remain at rest and thus permit the first rack bar to move upwardly one space so as to carry the "0" type thereon into alinement with the type numerals 9 on the other two type-bars. This total 990 is printed in the manner previously described, and upon the return stroke of the rack frame F the accumulator frame is moved rearwardly so that the downward movement of the type-bars will not disturb the adding wheels of the accumulator which were moved back to zero by the upward movement of the type-bars. This rearward movement of the accumulator frame is effected by the cam 113 and arm 114, previously described, through

means of a pinion 117^a loosely mounted on the sleeve 115 which carries said cam and the rack 118^a on the rack frame F which was engaged by the pinion 117^a when the 5 cam arm 157 moved said sleeve 115 laterally in the direction indicated by the arrow in Fig. 13. The pinion 117^a is also loosely mounted on the sleeve 115, and it is provided with a spring-actuated pawl 124^a 10 that cooperates with a one-toothed ratchet 125^a rigidly secured to the sleeve 115, said pawl and ratchet being so arranged that the pawl will travel idly over the ratchet on the forward stroke of the rack frame F and thus 15 permit the accumulator frame to remain in operative position on the forward stroke of the operating handle or when the type-bars move upwardly. Upon the return stroke of 20 the ratchet 125^a and moves the sleeve 115 and the cam 113 thereon, thus causing the accumulator frame to move rearwardly so that the adding wheels thereon will not be engaged by the racks 101 on the type-bars 25 when said type-bars move downwardly. The dogs 106, which cooperate with the adding wheels of the accumulator, are raised or moved into an inoperative position when the total-key is depressed so as to permit the 30 adding wheels to rotate rearwardly when they are engaged by the racks on the upward stroke of the type-bars. The means herein shown for moving the dogs 106 into an inoperative position consists of a trans- 35 versely extending rod 160 (Fig. 4) arranged under the dogs 106 and carried by a pair of arms on a rock shaft 161 which is provided with a depending arm 162, as shown in Figs. 1, 3 and 4. The total-key lever is provided 40 with an upwardly projecting extension 163 that engages a lug 164 on the arm 162 when the total-key is depressed and thus rocks the shaft 161 so as to cause the rod 160 to move upwardly and disengage the dogs 106 from 45 the adding wheels of the accumulator.

Sub-total key.—In order that a sub-total may be taken of some of the numbers in a column of figures which are to be added, I have provided the machine with a sub-total 50 key 156^a which is mounted on a key lever that is provided at its rear end with a cam arm 157^a that cooperates with a disk 158^a on the sleeve 115, said cam arm 157^a being so designed that the depression of the sub- 55 total key will cause the sleeve 115, previously described, to move laterally in the direction indicated by the arrow in Fig. 13, far enough to disengage the pinion 117 from its cooperating rack but not far enough to 60 carry the pinion 117^a into engagement with its cooperating rack. If the operating handle is pulled forwardly after the sub-total key has been depressed a total of the numbers which have been previously registered 65 in the accumulator, will be printed and sub-

sequently re-registered in the accumulator. This is due to the fact that the depression of the sub-total key moved the pinions 117 and 117^a into a neutral position with respect to their cooperating racks on the rack frame 70 F so that said frame will move forwardly and return to normal position without causing the cam 113 to operate, thus leaving the accumulator frame in its normal position so that the racks 101 on the type-bars will engage the adding wheels of the accumulator 75 on both the upward and downward strokes of said type-bars. On the upward stroke of the type-bars the adding wheels of the accumulator are rotated rearwardly until they are stopped by the stop pawls of the accumulator, thereby printing the total of the numbers which have been previously registered. After this total has been printed the type-bars move downwardly and as they engage 80 the adding wheels of the accumulator on the downward stroke they will restore said adding wheels to the position they occupied before the type-bars moved upwardly on the forward stroke of the rack frame. The sub- 85 total key lever is also provided at its rear end with an upwardly projecting extension 163^a similar to that on the total key lever for causing the dogs 106 of the accumulator to be disengaged from the adding wheels 90 when the sub-total key is depressed.

Error key.—The machine is provided with an error-key 165 that is mounted on a key lever which is provided at its rear end with an upwardly projecting arm 166 that is 100 adapted to engage an arm 167 on the rock shaft 100 that carries the accumulator frame and move said frame rearwardly or into an inoperative position whenever the error-key is depressed. The depression of the error-key lever also causes a stop arm 168 to be moved upwardly into the path of movement of the rod 27 which forms part of the type-bar-operating mechanism, said stop arm 168 being connected to a shaft provided with an 105 arm 169 that has a laterally projecting pin 170 which lies under the error-key lever, as shown in Fig. 1. If the operator thinks that he has made a mistake in setting up a number he depresses the error-key 165 before he pulls the operating handle of the machine forwardly, thereby causing the accumulator to be moved into an inoperative position so that no numbers will be registered in the accumulator, and also moving 110 the stop arm 168 into such a position that it prevents the operating handle from being pulled completely forward. The operating handle moves forwardly far enough, however, to permit the number that has been set 115 up to be seen through the sight opening 24 in the casing, but said operating handle cannot be moved forward far enough to cause the printing mechanism to operate. If the number that has been set up is incorrect the 120 125 130

operating handle is released so as to restore the parts to normal position and the error-key is released, but if the number that has been set up is correct the operator merely 5 releases the error-key and continues the forward stroke of the operating handle so as to cause the number to be printed. The error-key, total-key and sub-total-key, and also various other elements of the machine which 10 are actuated positively in one direction, are restored to normal position by means of suitable coiled springs connected thereto.

Repeat key.—A repeat key 171, shown in Fig. 2, is provided for enabling a number 15 that has been set up in the machine to be printed several times by merely pulling the operating handle of the machine forwardly several times. Said repeat key is carried by a key lever that is provided at its rear end 20 with an upwardly projecting arm 172 (Fig. 3) having a pair of forwardly projecting extensions 173 which lie under the pinion 131 which forms part of the mechanism that winds up the spring 129 which restores the 25 pin carriage to normal position. When the repeat key is depressed the extensions 173 on the arm 172 of said repeat key lever move upwardly and disengage the pinion 131 from its coöperating rack 130 on the rack 30 frame F, thereby permitting said rack frame to be moved back and forth without affecting the position of the pin carriage B and consequently causing the number that has been set up at the previous operation to be 35 printed as many times as the operating handle is moved forwardly.

Operation.—In order that the operation of the machine may be perfectly clear, I will describe the movements of the various 40 parts of the machine during the operation of printing the numbers 972,000 and 18,000 and taking the total of these numbers. When the digit key 9 is depressed the extension 14 on the arm 13 of the digit key lever 9 engages the first pin in the top horizontal row 45 of pins on the pin carriage and forces said pin forwardly so that it projects beyond the front face of the pin carriage, the downward movement of the digit key lever 9 causing the escapement mechanism to operate 50 and thus permit the pin carriage to move one step to the left, looking from the front of the machine. The second vertical row of pins on the pin carriage is now in 55 alinement with the extensions on the arms 13 of the key levers so that when the digit key 7 is depressed the extension 14^b on the arm 13 of said key lever engages the second pin in the third horizontal row of pins from 60 the upper edge of the pin carriage, the pin carriage moving another step to the left when the digit key 7 is released. The digit-key 2 is then depressed so as to cause the extension 14^c to engage the third pin in the 65 ninth horizontal row of pins from the top

of the pin carriage and move said pin forwardly. The number is completed by depressing the zero key 3 which causes the escapement mechanism to be thrown out of operation and the rack bar 79 to be thrown 70 into mesh with the pinion 80 on the escapement shaft, the pin carriage moving to the left until the stop 81 on the under side of the rack bar 79 engages the lug 74 on the zero key 3. As the pin carriage started to 75 move to the left the stop plate 44 started to move forwardly so that said stop plate is now in position to prevent upward movement of all of the type-bars at the left of the six righthand type-bars of the machine 80 which are to be used in printing the number 972,000. The pins in the pin carriage, which were moved forwardly by the depression of the digit keys, limit the upward movement of the three lefthand type-bars 85 of the group above-mentioned, and the zero stop plate 86 on the pin carriage limits the upward movement of the three righthand type-bars of said group, said zero stop plate having moved to the left with the carriage 90 after the locking plunger 90 was disengaged from said stop plate by the depression of the zero stop key 3. After the number has been set up in the manner described, the operator pulls the handle C' of the machine 95 forwardly, thereby releasing the type-bar-operating members 18 and permitting said members to move the six righthand type-bars upwardly until the shoulders 17 of the three righthand type-bars engage the lower 100 edge 91 of the zero stop plate 86, and the shoulders 17 of the three type-bars to the left engage the pins that project forwardly from the front face of the pin carriage B. Each of said three righthand type-bars 105 moves upwardly one space so as to bring the "0" type thereon into operative position, the fourth type-bar from the righthand side of the machine moving upwardly two spaces, the fifth type-bar seven spaces, and the sixth type-bar nine spaces, thus arranging the type numerals 9, 7, 2, 0, 0, 0, on the type-bars in horizontal alinement and the corresponding numbers 23 on the portions 110 22 of the type-bar-operating members in alinement with the sight opening 24 in the casing of the machine. The forward stroke of the operating handle causes the rack frame F to move forwardly, and as the rack 118 on said frame meshes with the pinion 117 on the sleeve of the cam 113 said cam will rotate and thus rock the accumulator frame rearwardly so that the adding wheels of the accumulator will not be engaged by the type-bars when said bars move upwardly. The spring 129, which coöperates with the shaft 70 of the pin carriage restoring mechanism, is wound up on the forward stroke of the rack frame F, as is also the spring 147 which coöperates with the 115 120 125 130

cam shaft 111 of the accumulator, and on the last portion of the forward stroke of the rack frame the oscillating member 60 of the printing mechanism is actuated so as to 5 rotate the cam shaft 56 of the printing mechanism in the direction indicated by the arrow in Fig. 4 so as to cause the hammers 51 to strike the plungers 4 which carry the type that have been set up or arranged 10 in printing position. On the return stroke of the operating handle the rack frame F moves rearwardly and during the first portion of the rearward stroke of said rack frame the oscillating member 60 of the printing mechanism is restored to normal position. Just before the rack frame reaches the end of its rearward stroke the cam 142 15 on the rack frame trips the locking dog 140 and thus releases the shaft 70 so that the spring 129 can rotate said shaft and thus cause the toothed segment 138 to move the pin carriage B back to normal position, the cam 69 on the upper end of the shaft 70 co-operating with the arm 68 to actuate the 20 comb plate 65 which withdraws the pins on the pin carriage from operative position, and the zero stop plate 86 on the pin carriage being restored to normal position when it engages the stationary stop 95 on 25 the track on which the pin carriage travels. The accumulator frame had moved back to normal position before the rack frame started to move rearwardly so that when the type-bars move downwardly the adding 30 wheels which co-operate with the three left-hand end type-bars, namely, the fourth, fifth, and sixth type-bars from the right-hand side of the machine, will rotate forwardly and thus register the number 35 972,000 in the accumulator, the adding wheels which co-operate with the three righthand type-bars remaining at zero because said type-bars did not move upwardly far enough to bring the racks 101 40 on the lower ends of same into operative 45 relation with said adding wheels. Just before the rack frame reaches the end of its rearward stroke the cam 155 on said frame trips the dog 153 and thus releases the cam 50 shaft 111 of the accumulator so as to permit said cam shaft to rotate in the direction indicated by the arrow in Fig. 4 and actuate any of the stop pawls of the accumulator 55 which have been moved rearwardly by the adding wheels. In the example given, namely, the printing of the number 972,000, none of the stop pawls of the accumulator were moved rearwardly owing to the fact 60 that none of the adding wheels made a complete revolution.

The printing of the number 18,000 is effected by depressing the digit keys 1 and 8 and the zero key 3 in the manner previously described, and then pulling the operating handle forwardly and releasing it after the

number has been printed, the number 18,000 being registered in the accumulator and added to the number 972,000 by the co-operation of the type-bars with the adding wheels and the co-operation of the cams 110 70 of the accumulator with the stop pawls that were moved rearwardly by the complete rotation of the adding wheels with which they co-operate. To obtain the total of these two numbers the operator depresses the total-key 75 156 which causes the sleeve 115 that carries the cam 113 to move laterally far enough to disengage the pinion 117 from the rack 118 and cause the pinion 117^a to engage the rack 118^a. The operating handle is then pulled forwardly, and as the accumulator frame remains in operative position at this time, the adding wheels thereof will co-operate with the type-bars on the upward stroke of said bars and thus arrest them in such a position 80 that the total of the numbers which have been registered in the accumulator will be set up or arranged in operative position with relation to the printing mechanism. This total is printed on the last part of the 85 forward stroke of the rack frame, and when said rack frame moves rearwardly the various parts with which it co-operates are restored to normal position. If it is desired to merely take a sub-total of the numbers 90 972,000 and 18,000, the operator depresses the sub-total key 156^a and thus shifts the sleeve 115 that carries the cam 113 into neutral position so that the adding wheels of the accumulator will be engaged by the type-bars when said type-bars move upwardly 95 and will also be engaged by said type-bars when they move downwardly, the adding wheels limiting the upward movement of the type-bars, thus determining the position 100 of the type thereon, and the downward movement of the type-bars operating to restore the adding wheels to the positions they occupied before the sub-total key was depressed.

In case the operator thinks he has made an error in setting up a number he depresses the error-key 165 so as to move the accumulator frame into an inoperative position and arrest the forward movement of the rack 115 frame before the printing mechanism operates, the error-key being released if the operator finds the number set up in the machine is correct or the operating handle of the machine being released if the operator 120 finds that the number is incorrect. To print the same number several times the operator merely depresses the repeat key 171 so as to disengage the pinion 131 on the shaft 70 from its co-operating rack 30 on the rack 125 frame and thus permit the rack frame to be thereafter moved forwardly and backwardly any desired number of times without causing the position of the pin carriage to be changed. In case the operator desires to 130

register one or more members in the accumulator without printing them on the paper he depresses the error-key 165 so as to arrest the forward movement of the operating handle prior to the operation of the printing mechanism and he then releases the error-key prior to the return or rearward stroke of the operating handle and restores said handle to normal position. By releasing 10 the error-key prior to the return stroke of the operating handle the accumulator frame will be swung inwardly prior to the downward movement of the type-bars and thus cause the number or numbers which have 15 been set up to be registered in the accumulator but not printed owing to the fact that the operating handle was not moved forwardly far enough to cause the printing mechanism to operate.

20 While I have herein described the machine as being used for printing and adding numbers, I do not wish it to be understood that the machine is limited to this exact use for it can be used for any of the other purposes for which adding machines are now generally used, such, for example, as multiplication, subtraction and division.

Having thus described my invention, what I claim as new and desire to secure by Letters Patent is:

30 1. A calculating machine comprising an operating shaft, type-bars provided with shoulders, stop pins under control of the operator which coöperate with said shoulders 35 to limit the movement of said type-bars in one direction and thus determine the position of the type thereon, an oscillating device coöperating with each type-bar and provided with a segmental-shaped rack that 40 meshes with rack teeth on the type-bar, springs which tend to move said oscillating devices in one direction, a yieldingly operated member which is adapted to overcome the force of said springs and restore said devices and the type-bars to normal position, and means connected to the operating shaft of the machine for moving said yieldingly operated member into an inoperative position.

50 2. A calculating machine comprising an operating shaft, type-bars provided with shoulders, stop pins under control of the operator which coöperate with said shoulders to limit the movement of said type-bars in 55 one direction and thus determine the position of the type thereon, an oscillating device coöperating with each type-bar and provided with a segmental-shaped rack that meshes with rack teeth on the type-bar, 60 springs which tend to move said oscillating devices in one direction, a yieldingly operated member which is adapted to overcome the force of said springs and restore said devices and the type-bars to normal position, 65 means connected to the operating shaft of

the machine for moving said yieldingly operated member into an inoperative position, and members connected to said oscillating devices and provided with indicating numbers which can be seen through a sight opening in the casing of the machine. 70

3. In a calculating machine, vertically disposed type-bars provided with rack teeth, a sector gear for each type-bar that meshes with said rack teeth, a segmental-shaped 75 member integral with said sector gear type-bars, and arranged on the opposite side of the axis thereof, numbers on the periphery of said segmental-shaped member that correspond to the type numerals on said type-bars, yielding means that tends to move said sector gear so as to raise said type-bars upwardly, and means for locking said sector gear against movement.

4. In a calculating machine, type-bars, a 35 pin carriage arranged to travel transversely of the type-bars and provided with pins which are moved into operative position by the depression of the key levers of the machine so as to determine the position of the type on the type-bars, a member on said carriage which moves automatically into position and prevents the movement of those type-bars which are not used during the printing of a number, and means for moving 95 said member into an inoperative position when the pin carriage moves back to normal position.

5. In a calculating machine, type-bars, a pin carriage provided with means under 100 control of the operator for arresting the movement of said type-bars in one direction so as to determine the position of the type thereon, a stop plate on said carriage for arresting the movement of the type-bars that 105 are not used during the printing of a number, automatic means for moving said stop plate into and out of operative position, and an accumulator comprising means for determining the position of the type on the type-bars when a total or sub-total is printed. 110

6. In a calculating machine, vertically disposed type-bars provided with shoulders, a movable pin carriage arranged to travel 115 transversely of said type-bars and provided with pins which are adapted to be arranged in operative position by means under control of the operator for engaging the shoulders on the type-bars which are used during the printing of a number, a stop plate on 120 said carriage which coöperates with the shoulders on those type-bars that are not used during the printing of the number, and means for causing said stop plate to move into operative position when the carriage 125 travels in one direction and to move back into inoperative position when the carriage returns to normal position.

7. In a calculating machine, type-bars, a carriage arranged to travel transversely of 130

- said type-bars, pins on said carriage which are adapted to be set up progressively to determine the printing position of the type on said bars, and a member on said carriage 5 separate and distinct from said pins which determines the printing position of the zero type on a plurality of said type-bars.
8. In a calculating machine, type-bars, a carriage arranged to travel transversely of 10 said type-bars, pins on said carriage which are adapted to be set up progressively to determine the printing position of the type on said bars, a member on said carriage separate and distinct from said pins which deter- 15 mines the printing position of the zero type on a plurality of said type-bars, means for causing said carriage to move step-by-step during the operation of setting up said pins, and independent means for causing said car- 20 rriage to move a plurality of steps so as to bring said zero-type-determining member into operative relation with the type-bars.
9. In a calculating machine, type-bars, a carriage arranged to travel transversely of 25 said type-bars and provided with pins which are adapted to be set up by the operator so as to determine the printing position of the type on said bars, an escapement mechanism for causing said carriage to 30 move step-by-step, a propelling means for said carriage, spaced stops for ar- 35 restsing said carriage at different points in its transverse movement, means under control of the operator for moving said stops into operative position and discon- 40 nnecting the carriage from said escapement mechanism, and a member on said carriage which coöperates with the type-bars to determine the printing position of the zero type on a plurality of said type-bars.
10. In a calculating machine, type-bars, a carriage arranged to travel transversely of 45 said type-bars and provided with pins which are adapted to be set up by the operator to 50 determine the printing position of the type on said bars, an escapement mechanism for causing said carriage to move step-by-step in one direction, zero key levers, mechanism 55 controlled by said levers for arresting the carriage at different points in its transverse movement, means for causing said mechanism to become operative and said escapement mechanism to be disconnected from the 60 carriage when one or another of said zero key levers is depressed, and a member on said carriage which coöperates with the type-bars to determine the printing position of the zero type on a plurality of type-bars.
11. In a calculating machine, type-bars, a carriage arranged to move transversely of 65 said type-bars, a zero stop plate and a set of pins on said carriage which coöperates with said type-bars to determine the print- 70 ing position of the type thereon, means for 75 setting up said pins or arranging them in operative position, and independent means for controlling said stop plate and causing it to coöperate with two or more type-bars so as to determine the printing position of a plurality of zero type simultaneously.
12. In a calculating machine, type-bars, a carriage arranged to travel transversely of 80 said type-bars and provided with a set of pins which coöperate with the type-bars to determine the printing position of the type thereon, a zero stop plate on said carriage which coöperates with the type-bars to de- 85 termine the printing position of a plurality of zero type simultaneously, an escapement mechanism for causing said carriage to move transversely step-by-step so as to bring said pins into operative relation with the type-bars, a locking device which holds said stop plate at rest during the step-by- 90 step movement of the carriage, and mechanism under control of the operator for releasing said stop plate and causing the carriage to move a plurality of steps at one operation so as to bring the stop plate into operative relation with a number of type-bars.
13. In a calculating machine, a carriage provided with a set of pins which are adapt- 95 ed to be set up progressively to determine the printing position of the type on the machine, a zero stop plate on said carriage which determines the printing position of a plurality of zero type simultaneously, mechanism for imparting a step-by-step 100 movement to said carriage on its forward stroke, means for normally preventing the zero stop plate from moving with the carriage, mechanism for releasing said zero stop plate and causing the carriage to move 105 a plurality of steps at one operation, means for restoring the carriage to starting position, and means for causing said zero stop plate to assume its normal position with relation to said carriage.
14. In a calculating machine, vertically 110 disposed type-bars provided with shoulders, a carriage arranged to move transversely of said type-bars, pins on said carriage which are adapted to be set up by the operator so 115 as to engage the shoulders on said type-bars and thus determine the printing position of the type thereon, a member on said carriage which coöperates with the type-bars that are not used during the printing of a num- 120 ber so as to hold said type-bars in an inoperative position, and a zero stop plate on said carriage which is adapted to coöperate with a plurality of type-bars so as to de- 125 termine the printing position of a plurality of zero type simultaneously.
15. In a calculating machine, vertically 130 disposed type-bars, a carriage arranged to travel transversely of said type-bars and provided with devices which are adapted to

- be set up by the operator so as to determine the printing position of the type on said bars, a movable member on said carriage which prevents the type-bars that are not used during the printing of a number from moving into operative position, means for moving said carriage back and forth across said type-bars, and means for causing said member to move into operative position 10 when the carriage starts on its forward stroke and to return into an inoperative position before the carriage reaches its starting position.
16. In a calculating machine, vertically disposed type-bars provided with type numerals arranged one above another, a vertically disposed pin carriage arranged in operative relation to said type-bars and adapted to travel transversely back and forth 15 across same, horizontally disposed pins on said carriage corresponding in number to the total number of type on said bars and arranged in vertical rows, and means for progressively setting up the pins in said 20 different vertical rows as the carriage moves transversely of the type-bars so as to arrest the upward movement of the type-bars and thus determine the printing position of the type thereon.
17. In a calculating machine, type-bars, a carriage arranged to move transversely of said type-bars and provided with pins and a zero stop plate that coöperate with the type-bars to determine the printing position 25 of the type, an escapement shaft provided with a pinion that meshes with a rack on said carriage, an escapement mechanism controlled by the digit key levers of the machine, zero key levers which cause said 30 escapement mechanism to become inoperative, a rack bar which is adapted to be shifted into engagement with the pinion on the escapement shaft when the zero key levers are depressed and after said escapement mechanism has become inoperative, a 35 stop on said rack bar which coöperates with stops on said zero key levers, and a propelling means for said carriage.
18. In a calculating machine, type-bars, a carriage arranged to move transversely of said type-bars and provided with pins and a stop plate that coöperate with said bars to determine the printing position of the type thereon, an escapement shaft provided 40 with a pinion that meshes with a rack on the carriage, an escapement mechanism, digit key levers which control said escapement mechanism, zero key levers which move said escapement mechanism into an inoperative position, a frame controlled by said zero key levers and provided with a movable rack-bar that is adapted to engage a pinion on said escapement shaft, a propelling means for said carriage, and coöp- 45 erating means on said rack bar and on said zero key levers for arresting the carriage at different points in its travel.
19. In a calculating machine, an accumulator consisting of a movable frame provided with counting wheels, a cam coöperating with an arm on said frame for moving the frame out of and into operative position, a primary actuating member, and means whereby said cam makes one complete revolution on the forward stroke of 50 said primary actuating member and remains at rest on the return stroke of said primary actuating member.
20. In a calculating machine, a controlling mechanism for an accumulator frame consisting of a cam that coöperates with an arm on the accumulator frame, a sleeve to which said cam is connected, a pair of pinions carried by said sleeve and operably connected thereto by pawls and ratchets, a primary actuating member under control of the operator provided with racks which are adapted to coöperate with said pinions, one of said racks being normally in engagement with one of said pinions, a total key for shifting said sleeve so as to carry the other rack into engagement with the other pinion, and a sub-total key for shifting said sleeve so as to move both pinions into an inoperative position with respect to said racks. 55
21. In a calculating machine, a main operating shaft, reciprocating type-bars, devices under control of the operator for determining the printing position of the type on said bars, printing mechanism, means controlled by the main operating shaft of the machine for moving said type-bars into printing position and for causing said printing mechanism to operate, an error key, and means controlled by said error key for preventing the main operating shaft of the machine from moving far enough to cause said printing mechanism to operate. 60
22. In a calculating machine, a main operating shaft, type-bars, means under control of the operator for determining the printing position of the type on said bars, printing mechanism, an accumulator comprising a frame and counting wheels for registering the numbers that are set up in 65 the machine, mechanism controlled by the main operating shaft of the machine for actuating said type-bars, said printing mechanism and said accumulator frame, an error key, and means controlled by said error key for moving said accumulator frame into an inoperative position and for preventing the main operating shaft of the machine from being moved far enough to cause the printing mechanism to operate. 70
23. In a calculating machine, a main operating shaft type-bars, means under control of the operator for determining the 75

printing position of the type on said bars, printing mechanism, an accumulator comprising a frame and counting wheels for registering the numbers that are set up in 5 the machine, mechanism controlled by the main operating shaft of the machine for actuating said type-bars, said printing mechanism and said accumulator frame, an error key, means controlled by said error key for 10 moving said accumulator frame into an inoperative position and for preventing the main operating shaft of the machine from being moved far enough to cause the printing mechanism to operate, and visual means 15 for indicating the arrangement of the type on the type-bars which are in printing position.

24. In a calculating machine, a carriage provided with devices which are adapted 20 to be set up by the operator to determine the printing position of the type in the machine, means controlled by the operator for causing said carriage to move in one direction, a shaft provided with means for 25 gaging said carriage and moving it in the opposite direction, a spring for actuating said shaft, a primary actuating mechanism for storing up energy in said spring and locking it, and means for permitting said 30 spring to expand or unwind at a certain period in the cycle of operations of the machine so as to move said carriage back to its starting position.

25. In a calculating machine, a main operating shaft, a carriage provided with devices which are adapted to be arranged in operative position by means under control of the operator for determining the printing position of the type in the machine, 35 means for causing said carriage to move in one direction, an operating means for moving said carriage in the opposite direction, a spring-actuated shaft provided with a member which is adapted to engage and move 40 said operating means, means controlled by the main operating shaft of the machine for storing up energy in the spring that actuates said spring-operated shaft, and means for permitting said spring to 45 expand at a certain period in the cycle of operations of the machine.

26. In a calculating machine, a transversely moving carriage, a restoring mechanism for said carriage consisting of a 50 spring-actuated shaft and a member operated by same and operatively connected to said carriage, and a reciprocating operating member for storing up energy in the spring that operates said shaft and provided with 55 means for releasing said spring at a certain period in the cycle of operations of the machine.

27. In a calculating machine, a movable carriage, a restoring mechanism for said

carriage consisting of a member operatively connected to the carriage so as to move with same on the forward stroke of the carriage, a shaft provided with a device that is adapted to engage said member and move it back to normal position, a spring for actuating said shaft, means for storing up energy in said spring and thereafter locking the shaft, and means for releasing the shaft so that the device thereon can engage said member and move the carriage back to normal position.

28. In a calculating machine, a movable carriage, a restoring mechanism for said carriage comprising an oscillating arm provided with a toothed segment that meshes with a rack on the carriage, a member connected to said arm and provided with a track having an offset or shoulder, a shaft provided with a disk which carries a spring-actuated dog that projects into said track, 85 a spring for rotating said shaft in one direction, means for rotating said shaft in the opposite direction so as to store up energy in said spring, means for locking said shaft, and means for releasing said shaft so that 90 the dog mounted on the disk on said shaft can engage the shoulder on said track and thus actuate the arm which restores the carriage to normal position.

29. In a calculating machine, key levers, 95 a carriage which moves in one direction when the key levers are operated, a restoring mechanism for said carriage consisting of an arm operatively connected to the carriage and provided with a disk which has 100 a track thereon, said track being provided with an offset or shoulder, a shaft, a member connected to said shaft and provided with a spring-actuated dog that projects into said track, a spring for moving said shaft 105 in one direction, a pinion loosely mounted on the shaft and provided with a stop that cooperates with a stop on the member which carries said dog, a reciprocating rack frame provided with a rack that meshes with said 110 pinion so as to cause said spring to be wound up when said rack frame is moved in one direction, a device which locks said shaft, and means on said rack frame that trips said locking device so as to release 115 said shaft and thus permit said dog to engage the shoulder on said track and move the arm which restores the carriage to starting position.

30. A calculating machine comprising 120 type-bars, a printing mechanism, a carriage arranged to move transversely of the type-bars and provided with devices which determine the printing position of the type, an accumulator comprising counting wheels, 125 feeding pawls co-operating with same and a spring-actuated cam shaft for actuating said feeding pawls, a spring-actuated shaft

- for restoring said carriage to starting position, a reciprocating rack frame under control of the operator, and mechanism coöperating with said rack frame for actuating 5 said printing mechanism and for storing up energy in the spring which operates said cam shaft and the spring that operates the shaft that restores the carriage to starting position.
- 10 31. In a calculating machine, a main operating shaft, type-bars, a carriage arranged to move transversely of said type-bars and provided with devices which determine the printing position of the type, a 15 printing mechanism, a restoring mechanism for said carriage, an accumulator comprising a feeding mechanism, a reciprocating rack frame operatively connected to the main operating shaft of the machine, and 20 mechanism controlled by said rack frame for governing the operation of said printing mechanism, said carriage-restoring mechanism, and the feeding mechanism of the accumulator.
- 25 32. In a calculating machine, type-bars, each of which is provided with a shoulder, a carriage provided with devices that engage said shoulders and thus determine the printing position of the type on said bars, means 30 for causing said carriage to move in one direction when the key levers of the machine are operated, a restoring mechanism for returning said carriage to starting position, means for operating said restoring mechanism, and a repeat key for preventing said restoring mechanism from operating when the operating means for said mechanism operates.
- 35 33. In a calculating machine, type-bars, a 40 carriage provided with devices which determine the printing position of the type on said bars, means for causing said carriage to move in one direction when the key levers of the machine are operated, a restoring mechanism for returning said carriage to starting position, means operated by the forward movement of the main operating shaft of the machine for imparting movement to said restoring mechanism, and means under control 45 of the operator for preventing said restoring mechanism from operating when the main operating shaft of the machine is actuated.
- 50 34. In a calculating machine, a main operating shaft, a primary actuating member operatively connected to said main operating shaft, a printing mechanism operated by said member, a carriage provided with devices that determine the printing position of 55 the type in the machine, a restoring mechanism for said carriage operated by said primary actuating member, an accumulator comprising a movable frame, counting wheels on said frame, a feeding mechanism 60 for said counting wheels, and means controlled by said primary actuating member for governing the position of the accumulator frame and also causing the feeding mechanism for said counting wheel to become operative.
- 65 35. In a calculating machine, a main operating shaft a reciprocating rack frame operatively connected to said main shaft, a printing mechanism operated by said frame, a carriage provided with devices that determine the printing position of the type, a restoring mechanism for said carriage comprising a spring-actuated shaft, an accumulator comprising a spring-actuated cam shaft, coöperating means on said rack frame 70 and on both of said shafts for causing the springs which actuate same to be wound up when the rack frame moves in one direction, devices for locking said shafts, and means on said rack frame for tripping said locking devices when the rack frame moves in the opposite direction.
- 75 36. In a calculating machine, a primary actuating member consisting of a reciprocating rack frame operatively connected to the main operating shaft of the machine and adapted to move forwardly and backwardly when said main shaft is operated, a printing mechanism arranged to be operated by said rack frame during the forward stroke of 80 same, a carriage provided with devices under control of the operator which determine the printing position of the type in the machine, a restoring mechanism for said carriage comprising a spring, a movable accumulator 85 frame provided with counting wheels, a feeding mechanism for said wheels comprising a spring, means coöperating with said rack frame for controlling the position of the accumulator frame and for winding up both of said springs during the forward stroke of the rack frame, devices for locking 90 said springs after they have been wound up, and means on said rack frame for tripping said locking devices when the rack frame moves in the opposite direction.
- 95 37. In a calculating machine, a vertically disposed carriage, means for moving said carriage in one direction, means for restoring said carriage to normal position, horizontally arranged pins loosely mounted in said carriage for determining the printing position of the type in the machine, means for positively moving said pins into an operative position, and means for moving said pins out of an operative position after said carriage has been restored.
- 100 38. In a calculating machine, a vertically disposed carriage, horizontally arranged pins loosely mounted in said carriage for determining the printing position of the type in the machine, heads on one end of said pins, means for moving said pins into oper- 105
- 110
- 115
- 120
- 125

ative position, and a restoring mechanism for said pins comprising a slotted plate through which the pins pass, said plate being adapted to engage the heads on the pins 5 and move said pins into an inoperative position.

In testimony whereof I hereunto affix my

signature in the presence of two witnesses, this eleventh day of July, 1911.

JOHN I. HAYNES.

Witnesses:

WELLS L. CHURCH,
GEORGE BAKEWELL.
